UNITED STATES PATENT OFFICE.

FRANK W. REES, OF SEATTLE, WASHINGTON, ASSIGNOR TO SEES-ALL MANUFACTURING COMPANY, OF SEATTLE, WASHINGTON.

DESIGN FOR A REAR-SIGHT MIRROR FOR MOTOR-VEHICLES.

56,309.

Specification for Design.

Patented Sept. 14, 1920.

Application filed June 30, 1920. Serial No. 393,192. Term of patent 14 years.

To all whom it may concern:

Be it known that I, FRANK W. REES, a citizen of the United States, residing at Seattle, in the county of King and State of Washington, have invented a new, original, and ornamental Design for a Rear-Sight Mirror for Motor-Vehicles, of which the following is a specification, reference being had to the accompanying drawings, forming a part thereof.

In drawing Figure 1 is a view in elevation of a mirror constructed in accordance with my new design and Fig. 2 is a plan view of the same.

I claim—

The ornamental design for a rear sight mirror for motor vehicles as shown.

FRANK W. REES.
